UNITED STATES PATENT OFFICE.

RALPH A. SHAFFER AND EMMA A. MONTGOMERY, OF SHARON, PENNSYLVANIA.

COOKING-STOVE ATTACHMENT.

No. 902,919.

Specification of Letters Patent.

Patented Nov. 3, 1908.

Application filed June 22, 1908. Serial No. 439,815.

To all whom it may concern:

Be it known that we, RALPH A. SHAFFER and EMMA A. MONTGOMERY, citizens of the United States, residing at Sharon, in the county of Mercer and State of Pennsylvania, have invented a new and useful Cooking-Stove Attachment; and we do hereby declare the following to be a full, clear, and exact description of the invention, such as will enable others skilled in the art to which it appertains to make and use the same.

This invention relates to an improved attachment for the ovens of cooking stoves, ranges and the like, the same consisting of a supporting device for baking pans and the like, which is mounted in such a manner as to be capable of being rotated within the oven, thus enabling the pan or pans supported thereon to be reversed, end for end, without opening the oven door and without touching the pans with the hands.

The present invention has for its object to simplify and improve the construction and operation of this class of devices above referred to, and with these and other ends in view which will readily appear as the nature of the invention is better understood, the same consists in the improved construction and novel arrangement and combination of parts, which will be hereinafter fully described and particularly pointed out in the claims.

In the accompanying drawing has been illustrated a simple and preferred form of the invention; it being, however, understood that no limitation is necessarily made to the precise structural details therein exhibited, but that changes, alterations and modifications within the scope of the invention may be resorted to when desired.

In the drawing—Figure 1 is a sectional view taken vertically through a portion of a stove or range having the improvement applied to the oven. Fig. 2 is a plan view of the device, a part of the disk 19 being broken away. Fig. 3 is a perspective view of the shaft 12 and head 13.

Corresponding parts in the several figures are denoted by like characters of reference. The floor 5 of the oven and the bottom plate 6 of the stove or range are provided with centrally disposed apertures 7, 8, for the passage of a sleeve or thimble 9 having at its upper end an annular flange 10 resting upon the floor of the oven where the sleeve is thus supported. The lower end of the

sleeve which projects through the bottom plate of the stove is externally threaded for the reception of a nut 11 whereby the sleeve is securely retained in position without possibility of the leakage of smoke from the flue space between the plates 5 and 6.

The sleeve 9 affords a bearing for a shaft 12, having at its upper end a head or enlargement 13, preferably of square cross-section which is supported upon the flange at the upper end of the sleeve. The corners of the head 13 are provided with notches 14 affording seats for a ring or band 15, which latter when seated in said notches will be spaced on the sides of the head 13 sufficiently for the insertion of lugs 16 formed at the inner ends of four radiating arms 17 which may thus be readily connected with the head 13. The arms 17, which are provided at their outer extremities with upturned lugs 18 serve to support the disk 19 of perforated sheet metal or other suitable foraminous material upon which one or more baking pans or similar vessels may in turn be supported.

Suitably secured upon the lower end of the shaft 12, as by means of a set screw 20, is a beveled pinion 21 that meshes with a similar pinion 22 upon a shaft 23 which is supported for rotation in suitable bearings beneath the bottom plate of the stove; said shaft being provided with a crank 24 whereby it may be conveniently rotated for the purpose of imparting rotary motion to the shaft 12 and related parts.

The operation and advantages of this invention will be readily understood from the foregoing description taken in connection with the drawings hereto annexed. Baking pans or cooking vessels of any kind which are placed upon the supporting disk 19 within the oven may be reversed, or their position may be changed from time to time by manipulating the crank 24, thereby imparting rotary motion to the shaft 12 carrying the supporting disk. In this manner the contents of the pans may be alternately subjected to the greater or lesser degree of heat prevailing in different locations within the oven, and the contents may thus be baked, roasted or otherwise cooked evenly throughout and without danger of being burned or scorched.

Having thus described the invention, what is claimed is—

1. In a stove or range, an oven floor and a bottom plate, having alining apertures, a

sleeve extending through said apertures and having an annular flange resting upon the oven floor, and a nut threaded upon the lower end of the sleeve and engaging the 5 under side of the bottom plate; in combination with a shaft journaled in the sleeve and having an enlargement at its upper end, radiating arms extending from said enlargement, a foraminous disk supported upon 10 said arms, and means for rotating the vertical shaft.

2. In a stove or range, a bottom plate having alining apertures, a flanged sleeve extending through and secured in said apertures, a shaft journaled in the sleeve and having at its upper end an enlargement forming a head of square cross-section and having notches at the corners thereof, a ring seated in said notches, arms provided at 15 their inner ends with downward extending brackets engaging the ring and bearing upon the sides of the head, a foraminous disk supported upon the arms, and means for rotating the shaft.

25 3. In a device of the character described,

a bearing sleeve flanged at one end and having a nut threaded upon the opposite end thereof, a shaft journaled in the sleeve and having a square enlargement forming a head at its upper end, said head being provided 30 with notches at the corners thereof, a ring seated in the notches, arms provided at their inner ends with brackets inserted between the ring and the sides of the head and bearing upon the latter, a foraminous disk supported upon the arms, a beveled pinion secured upon the lower end of the shaft, and a countershaft supported for rotation and having at one end a crank and at the other end a pinion meshing with the beveled pinion 35 upon the shaft journaled in the sleeve.

In testimony whereof we have signed our names to this specification in the presence of two subscribing witnesses.

RALPH A. SHAFFER.
EMMA A. MONTGOMERY.
